UNITED STATES PATENT OFFICE

153,322

DESIGN FOR AN INSECT POISON CONTAINER

John B. Rosefield, Piedmont, Calif., assignor to
John B. Rosefield and John O. Rosefield, co-
partners doing business as An-Fo Manufactur-
ing Company

Application July 9, 1947, Serial No. 140,165

Term of patent 7 years

(Cl. D31—3)

To all whom it may concern:

Be it known that I, John B. Rosefield, a citizen of the United States, residing at Piedmont, in the county of Alameda and State of California, have invented a new, original, and ornamental Design for an Insect Poison Container, of which the following is a specification, reference being had to the accompanying drawing, forming part thereof.

Figure 1 is a top plan view of an insect poison container, showing my new design;

Figure 2 is a side elevation;

Figure 3 is a front elevation, and

Figure 4 is a rear elevation thereof.

I claim:

The ornamental design for an insect poison container, as shown.

JOHN B. ROSEFIELD.
